Attorney

UNITED STATES PATENT OFFICE.

CLARENCE F. GILCHRIST, OF TOLEDO, OHIO, ASSIGNOR TO THE ELECTRIC AUTO-LITE COMPANY, OF TOLEDO, OHIO, A CORPORATION OF OHIO.

DRIVING MECHANISM.

Application filed July 22, 1918. Serial No. 246,189.

To all whom it may concern:

Be it known that I, CLARENCE F. GILCHRIST, a citizen of the United States, residing at Toledo, in the county of Lucas and State of Ohio, have invented certain new and useful Improvements in Driving Mechanism, of which I declare the following to be a full, clear, and exact description.

This invention relates to a driving mechanism for use in the starting system of an internal combustion engine. More particularly considered, the invention comprises an automatic screw gearing applicable in the gear train intermediate the electric starting motor and internal combustion engine.

An object of this invention is to provide a driving mechanism intermediate the electric motor and engine, which has flexibility and elasticity, and in which there is no spring or similar elastic member in the direct line of power transmission.

Another object is to provide a type of gearing in which the driving connection and disconnection is made in an entirely automatic way.

Another object is to utilize a gearing unit which will automatically take care of variations in engine cylinder compression.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawings forming a part thereof, in which:

Figure I is a longitudinal sectional view taken through the gearing unit showing it in its disconnected position.

Figure II is a view similar to Fig. I but showing the unit in its connected position.

Figure III is a cross sectional view of the driving unit, taken on the line III—III of Figure I.

Figure IV is an elevation of an element of the driving unit; and

Figure V is another elevation of the element, shown in Figure IV.

Similar reference numerals refer to similar parts throughout the several views, and the cross sectional view is taken looking in the direction of the arrows.

In accordance with the drawings, I have shown an engine element 1, which in the present invention takes the form of the fly-wheel adapted to be directly connected to the crank shaft of an internal combustion engine. An electric motor 2 is positioned relative to the fly-wheel, so as to have operative connection therewith. The motor may be of any type effective for the efficient starting of the engine, such as the series wound type commonly used in this connection. The motor has a driving shaft 3 which is machined to have three sections of different diameters, a short section 4, adjacent the motor, forming a stop for the driving unit, as hereinafter described, a central section 5 of less diameter than the section 4, and an outer section 6, of less diameter than the central section. The end of the outer section 6 is screw threaded as indicated in Figures I and II, and with this threaded portion an internally threaded sleeve 7 is adapted to have threaded engagement, thereby having axial movement relative to the shaft. The outer end of this sleeve 7 is externally threaded to receive a holding nut 8, and adjacent its inner end the sleeve carries a pin 9 extending radially therefrom. From the point of attachment of the pin to the inner end of the sleeve, the internal diameter of the sleeve is increased above that of the threaded portion and machined so as to have a smooth cylindrical surface as shown at 10 in Figure I. The pin extends into the recess formed by this greater diameter of the sleeve, and is adapted to abut against the inner end of the threaded section of the shaft, preventing the removal of the sleeve from the shaft. The diameter of this inner end of the sleeve is such that the sleeve readily slides over the middle section of the shaft when the sleeve is moved axially toward the motor.

Mounted upon the sleeve 7 is a second sleeve 12, which has a length relatively less than that of the first named sleeve, and which is adapted to have axial and rotational movement relative to the sleeve 7. In the body of the sleeve, an angular slot 13 is cut in such a position that its direction relative to the axis of the cylinder or sleeve opposes that of the inclination of the screw 110

threads on the motor shaft, and in such a manner that the slot advances toward the inner end of the shaft. The slot 13 does not extend completely around the sleeve, but takes the form of a section of a spiral or screw thread, the inner end 14 of which lies adjacent the one end of the sleeve, and the outer end 15 of which lies approximately mid-way between the ends of the sleeve, as clearly illustrated in Figure IV and V. In the slot 13, the pin 9 is adapted to have movement.

The inner end of the sleeve 12 is outwarded to form an annular flange 17, and this flange is cut to form a series of lugs 18, equally spaced from each other as shown at Figure III. Mounted on the middle section of the shaft, is a pinion 19, which is normally in juxtaposition with the surface formed by the annular flange and lugs 17 and 18. A holding ring 20 is fixed to the periphery of the pinion, adjacent the outer end thereof, for a purpose to be described.

The resilient element of the driving unit is a coil spring 21, which is placed around the sleeves 7 and 12 in such a position that the inner end thereof abuts against the annular flange 17 of the outer sleeve. The outer end of the spring bears against the circular stop or washer 22, which is held in position adjacent the end of the motor shaft by the terminal nut 8, hereinafter described. The washer 22 serves also as the support for a cylindrical casing 23 which is attached thereto by means of machine screws 24. This cylinder extends over the resilient element, and its inner end is slotted to form a series of parallel fingers 25, between which the projecting lugs 17 are adapted to have longitudinal movement. The ends of these fingers are turned down in such a way that they insert over the annular ring 20 on the outer end of the pinion, and between the various teeth of the pinion, so that rotational force applied to the cylinder 23 is at once transmitted to the pinion by means of the beat-in fingers 25.

The normal inoperative position of the driving mechanism is illustrated in Figure I of the drawing. When power is applied to the motor, and assuming that the direction of rotation of the motor shaft is as indicated by the small curved arrow, the inertia of the driving unit permits a screwing motion upon the motor shaft which causes the pinion to move axially inward toward the engine gear 1. Because of the inertia of the driving element, there will be no rotation of the pinion, and in consequence, the meshing of pinion and gear is readily effected. Axial movement of the pinion continues until it comes into abutment with the collar 4 of the motor shaft.

It is evident that the rotational force of the motor must be applied gradually to the

fly-wheel of the engine when it is fully in mesh with the pinion, otherwise there is a possibility that the gear teeth will be stripped or the motor shaft will be broken. This gradual application of rotational force of the motor to the engine member is provided for in the spring element 21. As soon as the pinion has been stopped from inward movement, and the outer end of the pinion is in contact with the inner end of the sleeve 7, the pin 9 moves in the slot 13 in the direction of rotation of the motor shaft, and since the inclination of the slot is such that the rotating pin exerts a camming force upon the sleeve 12, tending to move it in an outer direction, the spring 21 is compressed until the inertia of the engine member is overcome, or the outer end of the sleeve 12 comes in contact with the terminal washer 22. By the time the full compression of the spring has been completed, the balance of forces between the passive engine element and the active motor element, will have been gradually attained, so that the engine may be started without any destructive or harmful results to the various parts of the mechanism. It should be noted that the driving intermediate the motor and engine member is from motor shaft to the inner sleeve, the inner sleeve to the outer sleeve, the outer sleeve to the connecting fingers 25, and from the fingers to the pinion and from the pinion to the engine gear. In other words, the spring does not directly transmit the driving torque of the motor but produces the necessary reaction between the pin and the wall of the slot and serves as a buffer for taking the jar, due to the sudden application of the rotational force of the motor.

While I have described my invention in more or less detail, and as being embodied in certain precise forms I do not desire or intend to be limited thereto, as on the contrary my invention contemplates broadly all proper changes, as well as the omission of immaterial elements and the substitution of equivalents therefor, as circumstances may suggest or necessity render expedient.

Having thus described my invention, what I claim as new and desire to secure by Letters Patent, is:

1. In a starting mechanism for internal combustion engines, the combination of an engine member; a driving shaft having a threaded portion; an internally threaded sleeve having threaded engagement with said shaft; a pin in said sleeve adjacent an end thereof; a second sleeve having a slot therein, inclined relative to the axis of the shaft, in which the pin is adapted to have movement, said second sleeve having radial circumferentially spaced lugs at one end thereof; a pinion slidably mounted on said shaft, having a ring at one end thereof; a spring mounted on said sleeves and adapted

- to exert pressure on said radial lugs; and a casing, one end of which is cut to form axially extending fingers between which the lugs are adapted to have axial movement, 5 the ends of said fingers being in-turned over said ring to engage the teeth of the pinion, said slot forming a camming surface for the pin whereby the spring is compressed when the pinion has full enmeshment with the engine member.
2. In a starting mechanism for internal combustion engines, the combination of an engine member; a driving shaft, a portion of which is threaded; a sleeve having 10 threaded engagement with said shaft; a pin in said sleeve; a second sleeve mounted on said first named sleeve, having a camming slot in its wall in which the pin is adapted to ride; a pinion mounted on said shaft; connections intermediate the pinion and said second sleeve; resilient means operative to oppose the camming movement of said slot when the pinion has moved into complete engagement with said engine member.
3. In a starting mechanism for internal combustion engines, the combination of an engine member; a driving shaft, a portion of which is threaded; a sleeve having 15 threaded engagement with said shaft; a pin in said sleeve; a second sleeve mounted on said first named sleeve, having a camming slot in its wall in which the pin is adapted to ride; and a flange having radially extending lugs; a pinion on said shaft adapted to make connection with said engine member; a casing attached to said first named sleeve having inwardly projecting fingers integral therewith, said fingers being adapted to have sliding engagement 20 with said lugs and said pinion whereby a positive drive may be obtained from the second named sleeve to the pinion; and resilient means operative to oppose the camming movement of said slot when the pinion has moved into complete engagement with said engine member.
4. In a starting mechanism for internal combustion engines, the combination of an
- engine member; a driving shaft, a portion 50 of which is threaded; a sleeve having threaded engagement with said shaft; a pin in said sleeve; a second sleeve mounted on said first named sleeve, having a camming slot in its wall in which the pin is adapted to ride; resilient means for opposing relative movement of said sleeve in one direction; a pinion mounted on said shaft; means operatively connecting said pinion and sleeves, said pinion being adapted to 55 have automatic axial movement into and out of engagement with the engine members.
5. In an engine starting mechanism, the combination of an engine member, a motor driven shaft, a driving member carried 60 thereby, means screw-threaded on said shaft for initially moving said driving member into engagement with said engine member, and means comprising a resilient compression member and a cam mechanism for subsequently transmitting a yielding driving torque from said shaft to said engine member.
6. In an engine starting mechanism, the combination of an engine member, a motor 65 driven shaft, a pinion having a bearing thereon, a member having threaded engagement with said shaft, means comprising a cam device and a resilient member for operatively connecting said pinion and said first member whereby upon initial rotation of the shaft the pinion is shifted into engagement with the engine member and upon further rotation the pinion yieldingly drives the engine member.
7. In an engine starting mechanism, the combination of an engine member, a motor driven shaft, a driving member thereon for 70 said engine member, means for operatively connecting said shaft and said driving member including a sleeve screw threaded on said shaft, a cam device between said sleeve and said pinion and a resilient member for varying the reaction between the co-operating parts of said cam device in accordance 75 with the relative movement thereof.

In testimony whereof, I affix my signature.
CLARENCE F. GILCHRIST.
